EARTH BORING MACHINE

Alan Jay Parrish, Paris, Ill.

Application July 30, 1940, Serial No. 348,577

7 Claims. (Cl. 255—20)

This invention relates to earth boring machines and more particularly to machines of the horizontal type for effecting accurate lateral borings beneath the ground and under existing structures wherever such boring operations are necessary.

The practices of trenching and tunneling usually employed in laying pipes, culverts and drains under existing structures is expensive and results in disturbing the normal impacted conditions of the soil underlying the structures because these methods include the steps of excavation, pipe laying and subsequent filling. The boring of laterals by horizontal earth boring machines has been resorted to but considerable difficulty has been experienced in these operations in obtaining accurate borings under all ground conditions. Tool breakage has been great and it has been the practice, when using augers drilling in clay, muck or the like, to repeatedly back off the tool to clear the same of the plug which packs around the tool. Machines having positive or automatic feed mechanism have excessive sudden loads thrown on them when encountering ground conditions affording great resistance resulting in tool or machine breakage.

The invention has for one of its objects the provision of a portable boring machine organization which can be used under all ground conditions and without tool breakage for installing pipes beneath existing structures including pavements, railway embankments and the like, and for making accurate point to point borings.

It is a further object of the invention to provide an improved boring machine organization which, due to its cooperating structural features and hand feed mechanism of greater mechanical advantage, may be easily advanced or retracted in drilling operations to permit increased continuous drilling range through clay, shale or rocky conditions.

Other objects include the economical production of a light weight simplified horizontal boring machine capable of heavy duty; the provision of a machine with improved hand feed mechanism and novel means of adjustment for controlled angle drilling; and the provision of a machine having a low center of weight with centralized power and feed connections, to provide a substantially balanced boring unit movable longitudinally in horizontal guiding supports.

Further advantages and objects of the invention will be apparent from the following detailed description of the invention and by reference to the accompanying drawings forming part of the specification. Like reference numerals represent

like parts throughout the several figures of the drawings, wherein:

Figure 1 is a perspective view of an earth boring machine in accordance with the invention.

Figure 2 is a vertical section on the line 2—2 of Fig. 3; Fig. 3 is a cross section on line 3—3 of Fig. 2; and Fig. 4 is a horizontal cross section on line 4—4 of Fig. 3.

Figure 5 is an enlarged view of the detachable boring tool guide.

Figure 6 is an end view partly in section illustrating a modified form of boring unit and supporting base structure.

Figure 7 is a longitudinal sectional view taken on line 7—7 of Fig. 6.

With particular reference to the embodiment of invention illustrated in Figs. 1 to 4, inclusive, of the drawings, 1 represents a base support vertically adjustable at one of its ends to provide for boring operations inclined from the horizontal. The base support comprises two longitudinally extending spaced parallel channel members 3 and 4, defining, with their inwardly directed flange portions, a trackway in which a wheeled carriage of a boring unit may be confined against movement other than a free rolling one longitudinally of the channel trackway. Cross members 5 and 6 underlying the ends of the channel members and suitably fastened thereto, preferably by welding, serve to complete the base frame and tie the channel members together in their parallel relationship. Cross ties 7 and 8 may be employed to further strengthen the base frame. Spacer blocks 9 may be interposed between the ends of cross tie members and the channel members to provide clearance for depending flanges on the wheels of the boring unit carriage so as to permit free rolling movement of the carriage lengthwise of the base support. Jack screws 10 having screw-threaded connection through nuts 11 welded to the end cross members provide for vertical adjustment of one end of the base for boring operations inclined from the horizontal.

Suitable pinion engaging means are provided at the upper flange portions of the channel members to cooperate with spaced pinions of a boring unit feed mechanism later to be described. In the illustrated embodiment of the invention, sectionalized rack bars 12 have their sections detachably secured to the upper flanges of the channel members by bolts 13 with the teeth in alignment for engagement with driven pinions 14 on opposite sides of the boring unit. While the racks for the pinions may be formed by aper-

turing the channel flanges or by forming the rack teeth integral therewith, the detachable section-
alized rack bars minimize the maintenance and repair expense incident to wear and breakage.

The base channel members are provided at end portions with apertures through the upper flanges adapted to register with apertures in the ends of a detachable auxiliary auger guide 15. Anchor pins 17 or other suitable fastenings passing through the registering apertures may be employed to fix the base and guide assembly.

The auxiliary auger guide comprises the bridging channel frame 16 arranged to overlie the base at its ends. The frame carries centrally thereof the split auger guide sleeve 18 comprising upper and lower members 19 and 20. The upper member is preferably formed integral with frame 16 by welding the sleeve member in a central recess of the frame. The lower member 20 is likewise made integral with bracket 21 pivotally connected at one end with frame 16 and detachably connected at the other end with the frame by pin 22 removably inserted through registering apertures in the frame 16 and the free end of the bracket. The sleeve 18 may constitute a guide for an auger of proper size or it may carry therewith for small augers a concentric reducer sleeve 23. The arrangement is such as to provide for removal of the guide from the auger at any time during a drilling operation. The guide sleeve, when connected with the channel base, is so arranged as to be coaxial with the driving chuck of an earth boring unit engaged within the channel trackway so as to receive therethrough with slight clearance the auger of the boring unit.

The boring unit includes a wheeled carriage portion having a main frame 24 formed of end angle members 25 and side angle members 26. These angle members are suitably fastened together preferably by electric welding to form an integral base frame having depending side and inwardly directed top flanges. The carriage is supported for rolling movement on four flanged wheels 27 mounted outside the base frame at the sides thereof on axles 28 extending transversely of the frame in tubular bearing supports 29 secured at their ends to the side angle members of the frame. The transverse spacing of the wheels is such that the wheeled carriage may be engaged within the channel trackway of the base for longitudinal movement therein or may be rolled clear of the base to facilitate handling and transportation of the machine.

Roller bearings are mounted in alignment in the bearing housings 30 supported centrally of the end members of the carriage frame and accommodate for rotation therein an earth boring tool drive shaft 31 which is provided with an extension beyond the front bearing to accommodate a chuck and flexible coupling 32 and has fixed thereto intermediate the bearings a large chain sprocket 33, associated with a driving chain 34 of a power transmission mechanism herein-after described.

A pinion shaft 35 is journaled at opposite sides of the carriage in bearings 36 and carries at each end a pinion 14 for engagement with the longitudinally extending rack bars on the channel base. The bearings are detachably associated with bearing supports 38 mounted on the carriage frame and are lubricated by grease cups 39. The bearing supports have their ends directed outwardly from the carriage frame for extension under the top flanges of the base frame close

to the surface thereof and assist in maintaining the carriage in alignment under any forces tending to lift its ends. The supports are arched in their central portions to provide mounting clearance for the transverse shaft and pinions above the main base. The pinion shaft forming part of the machine feed is positioned above the boring unit drive shaft at the rear of the sprocket and extends across the carriage on substantially its transverse center line. This provides for feed connection with the base at substantially the balance or center line of the units. The shaft is arranged to be rotated by a chain sprocket 40 keyed or otherwise fixed thereon adjacent one of the bearings. A conventional thrust collar 41 is mounted on the shaft adjacent the other bearing.

The sprocket 33 is rotated by separate power transmission connections supported above the carriage on angle uprights 42, four in number, suitably fastened as by welding at their lower ends to the carriage frame. The upper ends of the angle uprights are welded in pairs to spaced cross angle member 43 which detachably support aligned bearings 44 and 45. A shaft 46, journaled in the bearings, has its ends extended beyond the bearings, the shaft ends being arranged for detachable connection with hand cranks if manual operation is desired. A large sprocket 47 and a smaller sprocket 48 are affixed to the shaft 46 intermediate the bearings and the spaced pairs of upright angle supports.

A power shaft 49 parallel to shaft 46 is journaled in bearings 50 and 51 supported on transverse angle members 52-53 welded or otherwise fastened to the angle uprights. The power shaft is arranged at one end for driving connection with a flexible shaft 54 which may extend to the machine from any suitable source of driving power. A drive sprocket 55 fixed to power shaft 49 in alignment with the larger sprocket 47 serves to drive chain 56 to effect operation of the boring machine. The smaller sprocket 48 on shaft 46 is aligned with the large sprocket 33 on the boring tool drive shaft and drives the latter through sprocket chain 34.

The machine is provided with a manually operated feed device including a feed drive shaft 58 journaled in bearings 59 detachably supported on the front pair of angle uprights. The shaft is extended at one end and has mounted thereon, a hand crank 60 and a drive pinion 61 aligned with the driven pinion 40 and interconnected therewith by the sprocket chain 62.

Connection between the boring tool driving shaft and the boring auger 63 is effected by the combined chuck and flexible coupling 32. This chuck coupling consists of two sprockets 64 and 65 and an encircling double roller chain 66 engaging both sprockets. A small clearance between the sprockets and chain side plates allows freedom of movement to provide adjustment for angular misalignment of shafts. The sprocket 64 is provided with an elongated hub portion drilled to accommodate the boring unit drive shaft. The sprocket 65 is provided with an extended hub having a socket for accommodation of the shank of the auger 63 and a reduced diameter end portion adapted to provide seating engagement for a pipe supporting and engaging collar 68 provided with a set screw for fastening it to the end of the chuck for rotation therewith. The hub of sprocket 65 and the shank of the boring tool are provided with transverse bores 75 adapted to register and receive therein a sheer

pin 68 which is designed with sufficient strength to carry normal boring and drilling loads but so as to break under dangerous loads to avoid damage to tool and machine. The chuck coupling may be quickly taken apart by simply removing the chain connecting link which allows the chain to be lifted from the sprockets. The removal of the chain completely separates the parts.

The collar 68 may be fixed to rotate with the chuck by tightening the set screw or it may be freed by loosening the screw. This collar has a central sleeve extension and a peripheral flange provided with an annular groove having an outer sloping wall for receiving the end of a sheet metal pipe. The central sleeve portion is arranged to extend within the pipe in supporting engagement therewith and prevents collapse of the pipe under power applied to the end thereof by the collar. The outer sloping wall of the annular recess tends to force the wall of the pipe inwardly against the sleeve portion and prevents spreading. The collar is employed for rotating sheet metal pipe supported by the auger into position in the ground in prebored holes or during boring operations.

The boring element or auger 63 has at its forward or leading end a detachable cutter head or bit 70 provided with forwardly and outwardly extending cutting teeth or prongs 71. The structure may comprise a plurality of substantially duplicate auger sections successively joined together in the course of an extended drilling operation with the leading section detachably associated at its forward end with the head 70. The auger sections have spiral blades 63' which are cut away or are made to be discontinuous so as to provide a series of spaced spiral flights throughout the length of the auger. The flight sections, except at their forward or leading ends, have an overall diameter less than that of the cutter head. Leading ends of the sections are sharpened to provide radially extending cutting edges and are hardened and built up to substantially the same diameter as that of the bits of the cutter head so as to provide supplemental or secondary raised reaming cutter bars at the head of each flight section. The raised cutter bars may be provided as desired on any or all of the flight sections but generally the cutter bars may be omitted from flight sections rearwardly of the leading ones on each auger section.

The use of the secondary cutter bars at the leading end of the auger section eliminates the packing of dirt from the true auger section and produces a cleanly cut hole to the full diameter of the bit head. Furthermore, the objectionable torque build up due to packing of dirt about the auger is overcome, thus materially increasing the drilling distance for earth boring machines. In removing the boring tools when the desired depth of hole is reached, the secondary cutters keep removing all surplus dirt to the full diameter relieving the tendency to pack and speeding up materially the process of removing augers. In the removal of conventional types of augers, dependent upon the larger head being pulled backward with the forward rotating movement still in effect, the surplus build up had to be removed by the cutter head and became the cause of jamming and sticking drills even after the hole had been bored. This is completely eliminated by the improved auger structure.

The broken spiral flights affording spaces between adjacent spiral blade portions function,

when drilling in clay and other soils, to limit the packing and plug formation which usually results in such drilling operations. Continuous drilling is made possible in clay and the like by merely adding auger sections without removing the entering parts of the tool for cleaning. This avoids the difficulty heretofore encountered with conventional auger structures which pack and plug in a cumulative manner so as to make it necessary to frequently back off the tool for cleaning purposes. The plug of dirt which has a tendency to form at the leading end of the tool moves rearwardly of the tool as boring progresses but this plug is cut in pieces at the first point of flight interruption and is further severed by the succeeding separate sections as the dirt is passed toward the rear of the boring tool. The load factor is thus materially decreased and in clay drilling it is found that the plug which otherwise would form is actually removed from the hole in small cut lumps which progress rearwardly without putting a severe load on the boring machine or tool.

The overall diameter of the auger is determined by the size of the bore to be made and the auger guide sleeve presents a clearance between the inner surface of the sleeve and the auger which affords free operation but avoids the deflection of the auger in its progression into the ground. The machine performs accurately and satisfactorily in shale, strip mine use, and under other adverse conditions which usually present boring difficulties and serious tool deflection and breakage.

The machine hereinbefore described is arranged for manual operation or for connection to an external source of power of any suitable kind. The driving connections and connections between the feed pinions and rack bars are in centralized relationship to the movable boring unit, giving even distribution of the weight and the thrust from the auger. This avoids any tendency of the boring unit to tilt or go out of line in the trackway carriage and permits free rolling movement of the boring unit carriage longitudinally of the base under control of the feeding means. The auger is so constructed that in boring operations it assists in leading the machine and its clearance with relation to the sleeve guide is only that found necessary for free rotational movement therein. In actual boring operations, it is found that the boring units of the type described and those which are motorized can be progressed with only a small finger pressure applied to the hand crank. This enables an operator to practically feel ground conditions and his progress through walls and other obstructions.

In Figs. 6 and 7, there is illustrated a machine of modified form having increased mechanical advantage and modified cooperating base structures. The channel trackway of the modified form corresponds with that previously described with the important differentiation that the web portion of each channel between the inwardly directed flanges has welded thereto in reversed spaced relation longitudinally extending upper and lower angle members 72 and 73. The angle members are so positioned within the channels with bases welded to the channel as to present spaced inwardly directed flanges 75 and 76 defining a relatively narrow slot or trackway adapted to slidably receive, and support the boring unit 71.

The boring unit 71 includes a supporting fabricated frame preferably of welded construction.

This frame consists of a box-like base of welded side channels 78 and inverted end channels 79, a plurality of spaced vertical angle members 80, top 81 and intermediate horizontal supporting plate 82. The elements of the frame may be connected in any well known manner but in the preferred construction these elements are welded into an integral supporting structure to insure rigidity and strength and the use of standard structural units. The base of the boring unit is normally of less width than the distance between the inwardly directed guiding and supporting angle members of the base to permit free longitudinal movement of the boring unit in the trackway. However, the boring unit base is provided longitudinally of its sides with laterally extending horizontal flanges 83 adapted to be slidably received in supported relation in the trackways provided by the angles 72 and 73 of the main base frame. Flanges 83 may be conveniently provided by the use of standard angle members 84 welded longitudinally to the side of the base frame of the boring unit. The fits between the supporting flanges of the boring unit and the channel base trackway are such as to provide free but accurate longitudinal movement of the boring unit along the base.

Bearing housings 85 and 86 mounted in alignment on the end channels of the boring unit base carry roller bearings which support the boring tool drive shaft 87 which has an extension beyond the front bearing for driving connection with the chuck and flexible coupling 88 and has fixed thereto intermediate the bearings a large chain sprocket 89 of a power transmission mechanism hereinafter described.

The boring unit is arranged for driving connection with a flexible shaft 90 from a suitable source of power. Power transmission from the flexible shaft to the boring tool shaft includes 40 shaft 91 mounted in spaced bearings 92 at the top of the unit, drive sprocket 93 supported on said shaft between the bearings, shaft 94 mounted in spaced bearings 95 and 96 on the intermediate plate sprockets 98 and 99 fixed to shaft 100 and 101 trained over the respective aligned sprockets of the spaced parallel shafts. The arrangement is designed with a large gear reduction ratio in the chain and sprocket drive and multiple gear chains and sprockets are employed for transmission of substantial power from the flexible drive shaft.

Sliding movement of the boring unit in the trackway is accomplished only under the influence of manually operated feed means and under changeable gear ratios. For this purpose, a pinion shaft 102 is journaled at opposite sides centrally of the unit in bearings 103 and carries pinions 14 at the ends of the shaft for engagement with rack bars 12 on the channel trackway. The pinion shaft extends transversely of the unit frame above the boring tool drive shaft and carries intermediate its bearings fixed driving sprocket 104, worm gear 105 and associated clutch member 106 rotatably mounted on the shaft and clutch member 107 splined to the shaft for sliding movement under control of clutch lever 108 for engagement and disengagement with the worm gear. Worm 109 meshes with worm gear 105 and provides with said gear a ratio of approximately 25 to 1. The worm is driven by vertical shaft 110 rotatably supported in thrust bearing 111 at its lower end and extends through guide bearing 112 at the top of the unit for mounting a large hand

wheel 113 for rotating the shaft. An auxiliary or speed up drive for the pinion shaft is provided by hand wheel 114 mounted on shaft 115, rotatably supported in bearings 116 fixed to upright angle members of the frame. Shaft 115 extends at both sides of the machine to provide for optional mounting of the hand wheel and carries intermediate its bearings a small chain sprocket 117. A second shaft 118 is mounted on the frame 10 in bearings 119 below shaft 115 and carries intermediate its bearings the large chain sprocket 120 aligned with sprocket 117 and the small chain sprocket 121 aligned with sprocket 104. Sprocket chain 112 trained over sprockets 117-120 and sprocket chain 123 trained over sprockets 121 and 104 afford driving connections between shaft 115 and the pinion shaft.

The auxiliary or speed up manual feed is employed when the clutch is disengaged for the most 20 part in effecting rapid movement of the boring unit in its trackway for quick change of auger sections or the like or for other rapid adjustment of the boring unit. The main feed mechanism due to its large hand wheel and large gear reduction is employed mainly during drilling operations where slow progress is necessary. This high ratio feed presents such mechanical advantage and sensitive control that the boring unit is easily progressed during the most exacting drilling operations by only a slight pressure applied to the hand wheel. The manual feed mechanism is so sensitive and easily manipulated and the boring unit is so accurately guided in drilling operations by the supporting flange and trackway structure 35 that an operator can accurately feel drilling conditions throughout a complete drilling operation. This enables the operator to properly advance the machine in drilling speed as conditions justify without incurring tool breakage or stoppage of drilling operations. This is not possible with machines having automatic feed arrangements.

The operation of the machines in earth boring and pipe installation will be apparent from the foregoing description. However, when boring 45 operations or pipe laying operations are undertaken, it is only necessary to position the machines as to work and alignment and apply power to the boring tool. The cooperating channel trackway and sleeve guides insure accuracy and the manually operated feed mechanism progresses the boring units lengthwise of the trackway until its forward travel requires auger extensions for further boring. To add auger extensions or to withdraw a boring tool under power, the operation of the feed mechanism is reversed. Pipe 50 sections may be mounted on the auger and progressed as boring proceeds. New auger and pipe sections are added by retracting the machine and interposing these between already entered sections and the machine.

While the invention has been described in connection with preferred embodiments thereof, it is to be understood that the words which have been used are words of description rather than of limitation and that changes within the purview 65 of the appended claims may be made without departing from the true scope and spirit of the invention in all of its aspects.

This application is a continuation-in-part of my copending application Serial No. 160,162, filed August 20, 1937.

I claim:

1. In a boring unit of the character described, a base support of spaced parallel inwardly facing channel members having pinion engaging racks

along their upper flanges, a boring unit arranged for longitudinal movement between said channel members, interengaging means on the inner web portions of the channels and on the boring unit adapted to slidably support the boring unit for straight line movement in said base support, a pinion shaft journaled on said boring unit and having its ends overlying said racks, pinions fixed to ends of the shaft and arranged for engagement with said racks to effect movement of the boring unit in the base, manually operable means including a low ratio chain and sprocket reduction gear for rotating the pinion shaft to effect relatively quick movement of the boring unit along the base under conditions affording small resistance, and separate manually operable feed means of greater mechanical advantage including a worm and worm gear of relatively high ratio for moving the boring unit along the base support under conditions affording high resistance.

2. In a boring machine of the character described, a base support comprising spaced parallel channel irons with inwardly directed flanges each channel having a pinion rack along the upper flange thereof and a flange trackway along the web portion thereof for supporting and guiding a boring unit, a boring unit having a base portion with outwardly directed supporting flange members slidably engaged in the trackways of the base support to permit movement of said unit longitudinally of the base support, a pinion shaft journaled on the boring unit transversely thereof with ends overlying said pinion racks, pinions on said shaft engaging said racks, manually operable means including a hand crank and low ratio chain and sprocket gearing for rotating said pinion shaft and pinions, separate manually operable means including a hand crank and high ratio worm and gear drive for rotating the pinion shaft, and a manually operated clutch for connecting and disconnecting said worm and gear drive with the pinion shaft.

3. In a machine of the character described, a base support of spaced parallel channel members, an auger guide detachably mounted transversely of the channel members at one end of the base support and having a centrally disposed guide sleeve a portion of which is pivotally mounted to permit removal of the guide from a boring tool, a boring unit constructed and arranged for detachable driving connection with an auger extending through said guide and having a base arranged for longitudinal movement between said channel members, interengaging supporting guides comprising standard angle members fixed on the base support and boring unit providing straight line sliding movement of the boring unit in the base support, and manually operable feeding mechanism including rack and pinion connections between said base support and boring unit and selective manually operable reduction gearing having different gear ratios for rotating said pinions to effect feeding movement of the boring unit relative to the base support.

4. In a machine of the character described, a supporting base of spaced parallel channel members having pinion engaging racks along their upper flanges, a boring unit having a base arranged for longitudinal movement between said channel members, interengaging longitudinally extending supporting angle members welded respectively along the sides of the boring unit base and web portions of the channel member adapted

to provide sliding movement of the boring unit longitudinally of the base, manually operable means on the boring unit including selective reduction gearing and driven pinions meshing with said racks for feeding the boring unit in a straight line along said base, said racks and pinions and said guides cooperating to maintain alignment of the boring unit in the base in all operations, said selective gearing comprising alternating usable worm gear and worm drive of low ratio and a sprocket and chain guide of higher ratio.

5. In a machine of the character described, a supporting base of spaced parallel channel members having pinion engaging racks along their upper flanges, a boring unit having a base and boring tool arranged for longitudinal movement between said channel members, interengaging supporting flanges on the boring unit base and web portions of the channel members adapted to provide sliding movement of the boring unit longitudinally of the base, a detachable guide at one end of the base for guiding the boring tool, said guide having a central split tool guide sleeve and pivotally mounted means for opening the sleeve for detachable association with the tool, manually operable means mounted in the boring unit including selective gearing of different ratio and driven pinions meshing with said racks for feeding the boring unit in a straight line along said base, said racks and pinions and said flanges cooperating to maintain alignment of the boring unit in the base in all operations.

6. In a machine of the character described, a supporting base of spaced parallel channel members having pinion engaging racks along their upper flanges, a boring unit having a base and boring tool arranged for longitudinal movement between said channel members, interengaging supporting flanges on the boring unit base and web portions of the channel members adapted to provide sliding movement of the boring unit longitudinally of the base, said boring unit comprising an upright frame, a boring tool drive shaft journaled on the unit base, a parallel intermediate shaft journaled on said frame intermediate its bottom and top, a power drive shaft journaled on the top of the frame arranged for connection with a source of power, a chain and sprocket reduction gear between the power drive shaft and the intermediate shaft and a separate chain and sprocket reduction between the intermediate shaft and the boring tool drive shaft, manually operable means mounted on the boring unit including selective gearing of different ratio and driven pinions meshing with said racks for feeding the boring unit in a straight line along said base, said racks and pinions and said flanges cooperating to maintain alignment of the boring unit in the base in all operations.

7. In a machine of the character described, a supporting base consisting of spaced parallel channel members having pinion engaging racks along their upper flanges, a boring unit having a base and frame of welded standard structural members arranged for longitudinal movement between said channel members, interengaging means on the boring unit base and supporting base adapted to provide accurate longitudinal movement of the boring unit in the supporting base, said boring unit comprising a plurality of vertically spaced longitudinal supports on said frame, a boring tool drive shaft journaled in

spaced bearings on the base of the unit and having at one end thereof a frangible and flexible connection for detachably receiving a boring tool, a power drive shaft journaled on the uppermost horizontal supports on said frame arranged for connection with a source of power, a parallel intermediate shaft journaled on frame supports intermediate said boring tool shaft and said power drive shaft, reduction gearing connecting the power drive shaft and intermediate shaft, re-

duction gearing connecting said intermediate shaft and said boring tool shaft, manually operable means comprising manually selective gearing of high and low ratios and driven pinions 5 meshing with said racks for feeding the boring unit in a straight line along said supporting base, said high ratio gearing comprising chain and sprocket drive and said low ratio gearing comprising a worm and gear drive for said pinions.

10

ALAN JAY PARRISH.
